FORMER HEAD FOR BARBED WIRE
MANUFACTURING MACHINE

Ivan L. Sommerville, Channelview, Tex.

Application February 20, 1953, Serial No. 337,974

4 Claims. (Cl. 140—63)

1

This invention relates to former heads for barbed wire machines and more particularly to a former head in which the wrapping pin or pins are easy to replace and are freed from the function of rotationally driving the former barrel.

It is among the objects of the invention to provide an improved former head for a barbed wire manufacturing machine which head can be installed in an existing machine with no modification of the machine construction to operate in the well known manner to wrap barb forming wire lengths around a main wire strand at locations spaced apart along the main wire; which includes a minimum number of simplified parts for performing the wire wrapping operation; which is constructed to drive the former barrel from the former gear independently of the barb forming pins so that the pins are not subjected to barrel driving forces and can be formed of a hard steel alloy to resist rapid wear; which includes means which firmly supports the wrapping pins and which is readily accessible for replacement of worn or broken pins when necessary; which can be used to form either two point or four point barbs, as may be desired; and which is simple and durable in construction, economical to manufacture, easy to install and service, and efficient and effective in operation.

Other objects and advantages will become apparent from a consideration of the following description and the appended claims in conjunction with the accompanying drawings wherein:

Figure 1 is a top plan view of a barbed wire manufacturing machine including a forming head illustrative of the invention;

Figure 2 is a transverse cross sectional view on the line 2—2 of Figure 1;

Figure 3 is a perspective view of a former head illustrative of the invention;

Figure 4 is a longitudinal cross sectional view on the line 4—4 of Figure 3;

Figure 5 is a transverse cross sectional view on the line 5—5 of Figure 4; and

Figure 6 is a fragmentary, longitudinal cross sectional view on the line 6—6 of Figure 4.

With continued reference to the drawings, the barbed wire machine includes a top frame, generally indicated at 10, supported on a bottom frame, generally indicated at 11, within which the spooling mechanism of the machine is disposed. The barb forming mechanism is disposed above and mounted on the top frame 10 and includes a drive shaft 12 journaled in the top frame and carrying a chain sprocket 13 which is driven by a drive chain 14 from the power-operated spooling mechanism of the machine. A gear shaft 15

2

is journaled on the top frame by the spaced apart bearing structures 16 and 17 in spaced apart and parallel relationship to the drive shaft 12 and carries, intermediate its length, a main spur gear 18. The drive shaft 12 carries a spur gear 19 which meshes with the main gear 18 to drive the main gear and the gear shaft 15 and the feeding means for the barb forming wire.

A bearing bracket 20 is mounted on the top frame 10 adjacent the side of the main gear 18 remote from the gear 19 and a barb forming head, generally indicated at 21, is journaled in the bearing bracket 20 and driven by the main gear 18 in a manner to be later described in detail.

10 A main wire strand, as indicated at 22, extends through the head 21 and through a wire feeding mechanism, generally indicated at 23 and driven from the drive shaft 12, to the spooling mechanism disposed below the top frame 10 and,

15 20 at the end of the machine remote from the feeding mechanism 23, the main wire strand 22 is carried under a guide roller 24 and through suitable tensioning means so that it extends in a straight condition from the guide roller 24 to the feeding mechanism 23 through the barb forming head 21.

The machine forms barbs on the main wire strand 22 at locations spaced apart along this main wire and is capable of forming either four point barbs or two point barbs, as may be desired. Assuming that the machine is set to form four point barbs, strands 25 and 26 of barb forming wire are led in from the respectively opposite sides of the machine to the main wire strand 22 and have their ends disposed one above and one below the main wire strand adjacent the rear end of the forming head 21.

The cross strand 25 extends through a wire feeding mechanism, generally indicated at 28, which is periodically operated in timed relationship to the rotation of the gear shaft 15 by a link 30 pivotally connected at one end to a crank 31 connected at its other end to the wire feeding mechanism 28, the link 30 being connected at its end remote from the crank 31 to a crank 32 mounted on a shaft 33 journaled in the top frame 10 of the machine and driven at the same speed as the gear shaft 15.

The cross strand 26 extends through a wire feed mechanism, generally indicated at 35, actuated by a link 36 connected at one end to a crank 37 mounted on the adjacent end of the gear shaft 15, the link 36 being connected at its other end to a crank 38 connected to the wire feed mechanism 35.

The wire feed mechanisms 28 and 35 are si-

multaneously operated at periodic intervals in timed relationship to the main wire feed means 23 so that the cross strands 25 and 26 are advanced to extend their ends adjacent the main wire across the main wire a distance sufficient to form a four point barb each time the main wire is advanced a predetermined amount through the main wire feed 23. The forming head 21 is operated in timed relationship to the operation of the wire feeding means 28 and 35 to wrap the portions of the cross strands advanced across the main wire into barbs immediately after the cross strands have been advanced, to provide the barb-forming wire and to then release the wire wrapped about the main strand to form the barb.

Wire shearing means for cutting off the cross strands immediately after the barb has been formed is located at the rear end of the forming head 21 and includes a pair of stationary shear elements 40 and 41 located at respectively opposite sides of the rear end of the forming head, and a movable shear element 42 disposed between the stationary shear elements rearwardly of the forming head and mounted on a lever 43 pivoted on a fulcrum bearing 44 and engaging a cam 45 on the gear shaft 15 and moved relative to the stationary shear elements to shear the cross strands 25 and 26 immediately after the barb is formed on the main wire strand by the forming head.

As barbed wire manufacturing machines of the character indicated are old and well known to the art, a further illustration and description of the machine is considered unnecessary for the purposes of the present disclosure. If further details as to the construction and operation of the machine are desired, reference may be had to Patent Number 519,633, patented May 8, 1894, by I. A. Kilmer for "Wire Barbing Machine" and to various subsequent improvement patents in this art.

The forming head 21 of the present invention includes a substantially cylindrical, tubular gear 50 having a bore of substantially uniform diameter extending coaxially therethrough and having a spur gear formation 51 intermediate its length with cylindrical bearing formations 52 and 53 disposed one at each side of the gear formation 51. The tubular gear is provided with oil holes 54 and 55 in the bearing formations 52 and 53 respectively and with an internal screw thread formation 56 in the bore thereof at one end of the gear. An end closure plug 58 has an external screw thread formation 59 threaded into the screw thread formation 56 of the gear 50 so that the end plug closes the corresponding end of the gear and this end plug is provided at one end with an outwardly extending annular flange 60 which overlies the adjacent end of the gear 50. A recess 61 extends into the plug 58 from the inner end of the plug and this recess is of non-circular cross sectional shape, extending diametrically of the cylindrical plug 58 and having spaced apart and substantially parallel side surfaces, as indicated at 62 and 63 in Figure 5, equally spaced from and parallel to a diameter of the plug. The plug is provided with a centrally located aperture 64 through which the main wire strand 22 extends and is provided with wrapping pin receiving holes 65 and 66 disposed at respectively 70 opposite sides of the central aperture 64 and equally spaced from this central aperture.

A tubular barrel 68 is slidably mounted in the gear 50 and has a coaxial bore 69 reduced at one end to provide a restricted passage 70 for the 75

main wire strand, this restricted passage registering at the end of the barrel 68 to which it opens with the central aperture 64 in the end closure plug 68.

5 At its end in which the restricted passage 70 is provided, the barrel 68 is reduced to provide an extension 71 having flat sides substantially parallel to and equally spaced from a diameter of the cross sectional area of the barrel which 10 extension fits closely into the recess 61 provided in the closure plug 58 threaded into the gear 50. With this arrangement, the closure plug 58 provides a driving connection between the gear 50 and the barrel 68 through the extension 71 of 15 the barrel so that the barrel is rotated with the gear.

The barrel 68 is provided with wrapping pin receiving holes 72 and 73 disposed at respectively opposite sides of the wire passage 70 and registering 20 respectively with the pin receiving apertures 65 and 66 in the plug 58.

A wrapping pin 74 of elongated, cylindrical shape, is pressed at one end into the pin receiving hole 72 in the barrel 68 and projects from the 25 end of the barrel adjacent the plug 58 through the pin receiving aperture 65 in the plug and a similar wrapping pin 75 is pressed at one end into the hole 73 in the barrel and projects from the corresponding end of the barrel through the pin 30 receiving aperture 66 in the closure plug.

When the barrel extension 71 is fully seated in the recess 61 in the closure plug, as illustrated in Figure 4, the pins project beyond the outer end surface of the closure plug a distance sufficient to engage the ends of the cross strands 25 and 26 crossing the main wire 22 one above and one below the main wire so that, upon rotation of the gear 50, the end plug 58 and the barrel 68, the wrapping pins are revolved around the main wire to wrap the cross strands around the main wire to form the barb. As soon as the barb is formed the pins are retracted inwardly of the gear so that their outer ends are disposed flush with or slightly inwardly of the outer end surface of the plug 58 by means presently to be described, so that they completely release the wire from which the barb is formed immediately after the barb has been wrapped on the main wire strand. The extent to which the pins project outwardly of the outer end surface of the plug 58 is less than the length of the barrel extension 71 and the depth of the recess 61 so that the extension 71 will remain engaged in the recess 61 in the plug 58 when the pins are fully retracted.

As the pins 74 and 75 are not subjected to any driving force between the gear 50 and the barrel 68 and are entirely free in the apertures 65 and 66, these pins may be formed of a specially hard steel alloy, which may have considerable brittleness along with high wear resistance characteristics so that the pins will not be broken, and will wear for an extended period of time.

If the pins should become worn or broken, access to the pin-receiving end of the barrel 58 for replacement of the pins can be readily obtained by merely threading the closure plug 58 out of the corresponding end of the gear 50, the closure plug being provided in its outer end surface with recesses 77 and 78 providing spaced apart and substantially parallel flats engageable by a wrench for turning the plug relative to the gear.

The gear 50 is journaled by its bearing formations 52 and 53 in the bearing bracket 20 so that the gear formation 51 thereof is in mesh

with the gear 18 on the gear shaft 15, the forming head thus being continuously driven while the machine is in operation. A face cam is mounted on the shaft 15 at the side of the gear 19 remote from the rear end of the forming head and a rocking yoke 81 is pivotally mounted on the main frame for rocking movement about an axis disposed below and substantially at right angles to the rotational axis of the forming head 21. A cam following roller 82 is journaled on the yoke 81 and bears against the face of the cam 80 and a spring 83 is connected between the other ends of the yoke and the top frame 10 of the machine and resiliently maintains the cam follower 82 in engagement with the face of the gear 80.

The barrel 68 of the forming head projects outwardly of the end of the gear 50 remote from the end plug 52 and this outwardly projecting portion of the barrel is provided with spaced apart, annular bead or collar formations 85 and 86 providing between them an external annular groove 87. The yoke 81 is provided with a notch receiving the portion of the barrel 68 between the collar formations 85 and 86 and with suitable abutment means engaging the inner sides of these collar formations to move the barrel 68 longitudinally of the gear 50 when the yoke 81 is rocked by the cam 80. The cam has a flat annular surface disposed substantially in a plane perpendicular to the rotational axis of the shaft 15 extending partly therearound and has a lobe formation which engages the cam follower 82 immediately after the ends of the cross strands 25 and 26 have been wrapped on the main wire strand 22 to form a barb, to retract the wrapping pins 74 and 75 out of engagement with the wire of the barb which has just been formed. The lobe on the cam 80 holds the wrapping pins retracted while the cross strands 25 and 26 are being advanced across the main wire strand 22 to provide material for a new barb and projects the cam only for the period necessary to wrap the ends of the cross strands around the main wire strand to form the barb.

If it is desired to form two point barbs instead of four point barbs, it is necessary only to omit one of the cross strands 25 or 26 and to omit the corresponding wrapping pin from the forming head 21, the forming head then wrapping the single cross strand about the main wire strand to form two point barbs at spaced apart locations along the main strand.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. A former head assembly for a barbed wire manufacturing machine comprising a tubular former gear having a spur gear formation intermediate its length, cylindrical bearing formations disposed one at each side of said gear formation and internal screw threads at one end thereof, a closure plug threaded into said one end of said gear and having a recess of non-circular cross sectional shape in the inner end thereof, a centrally disposed main wire aperture

extending from said recess to the outer end surface thereof and at least one wrapping pin receiving aperture extending from said recess to the outer end surface thereof at a location spaced from said centrally disposed aperture, a tubular barrel slidably disposed in said gear and having on one end a formation of non-circular cross sectional shape received in the recess in said closure plug so that said closure plug constitutes a driving connection between said gear and said barrel, said barrel having a coaxial bore restricted at said one end thereof and registering with the centrally disposed aperture in said plug and extending at its other end out of the adjacent end of said gear and having at least one hole extending longitudinally thereof from the bore therein to said one end thereof and registering with said wrapping pin receiving aperture in said closure plug, a wrapping pin secured at one end in the hole in said barrel and extending through the wrapping pin receiving aperture in said plug, and a collar formation on the portion of said barrel projecting out of said gear for engagement by a machine element to impart longitudinal movement to said barrel relative to said gear.

2. A former head assembly for a barbed wire manufacturing machine comprising a tubular former gear having a spur gear formation intermediate its length, cylindrical bearing formations disposed one at each side of said gear formation and internal screw threads at one end thereof, a closure plug threaded into said one end of said gear and having a recess of non-circular cross sectional shape in the inner end thereof, a centrally disposed main wire aperture extending from said recess to the outer end surface thereof and at least one wrapping pin receiving aperture extending from said recess to the outer end surface thereof at a location spaced from said centrally disposed aperture, a tubular barrel slidably disposed in said gear and having on one end a formation of non-circular cross sectional shape received in the recess in said closure plug so that said closure plug constitutes a driving connection between said gear and said barrel, said barrel having a coaxial bore restricted at said one end thereof and registering with the centrally disposed aperture in said plug and extending at its other end out of the adjacent end of said gear and having at least one hole extending longitudinally thereof from the bore therein to said one end thereof and registering with said wrapping pin receiving aperture in said closure plug, a wrapping pin secured at one end in the hole in said barrel and extending through the wrapping pin receiving aperture in said plug, and a collar formation on the portion of said barrel projecting out of said gear for engagement by a machine element to impart longitudinal movement to said barrel relative to said gear, the recess in said closure plug having a depth and the recess engaging formation on said barrel having a length such that said wrapping pin is retractable to a position at which its outer end is substantially flush with the outer end surface of said plug without moving said barrel formation out of said recess.

3. A forming head for a barbed wire manufacturing machine comprising a tubular gear adapted to be journaled in machine carried bearings and driven by the associated machine, a tubular barrel mounted in said gear for sliding longitudinal movement, a closure plug on one end of said gear having a connection for

drivingly connecting the adjacent end of said barrel to the rotation of said gear, said barrel having a coaxial bore and registering with a centrally disposed aperture formed in said plug, collar means on the other end of said barrel for engagement by a machine element to impart longitudinal movement to said barrel relative to said gear, and at least one wrapping pin carried by said barrel and projecting longitudinally from the end of said barrel adjacent said closure plug through a hole formed in said plug.

4. A forming head for a barbed wire manufacturing machine comprising a tubular gear adapted to be journaled in machine carried bearings and driven by the associated machine, a tubular barrel mounted in said gear for sliding longitudinal movement, a closure plug on one end of said gear having a connection for drivingly connecting the adjacent end of said barrel to the rotation of said gear, said barrel having a

coaxial bore and registering with a centrally disposed aperture formed in said plug, collar means on the other end of said barrel for engagement by a machine element to impart longitudinal movement to said barrel relative to said gear, and at least one wrapping pin carried by said barrel and projecting longitudinally from the end of said barrel adjacent said closure plug through a hole formed in said plug, said wrapping pin comprising a body of hard metal alloy.
